ELEVATOR FOR OIL WELL DRILL PIPE OR THE LIKE

John F. Grundmann, 651 S. Irena Ave.,
Redondo Beach, Calif.

Filed July 6, 1959, Ser. No. 56,650

Term of patent 14 years

(Cl. D41—1)

FIG. 4.

FIG. 5.

Fig. 1 is a right side perspective view of an elevator for oil well drill pipe or the like embodying my new design;

Fig. 2 is a front perspective view thereof taken from the top;

Fig. 3 is a rear perspective view thereof taken from the top;

Fig. 4 is a left side perspective view thereof taken from the bottom; and

Fig. 5 is a bottom plan view thereof.

This application is a continuation-in-part of my co-pending application Serial No. D-54,834, filed March 4, 1959, now abandoned.

I claim:

The ornamental design for an elevator for oil well drill pipe or the like, as shown.
